SHOULDER SUPPORT FOR TELEPHONES

Lyle J. Martinsen, 315 E. 6310 South
Murray, Utah 84107

Filed Mar. 10, 1975, Ser. No. 556,764

Term of patent 14 years

Int. Cl. D14—03

U.S. Cl. D26—14 A

FIG. 1

FIG. 2

FIG. 3

FIG. 5

FIG. 6

FIG. 4

FIG. 7

FIG. 1 is a perspective view of a shoulder support for telephones showing my new design;

FIG. 2 is a side elevation thereof;

FIG. 3 is an end elevation as seen from the right of FIG. 1;

FIG. 4 is an end elevation as seen from the left of FIG. 1;

FIG. 5 is a top plan view of FIG. 1;

FIG. 6 is a bottom plan view thereof; and

FIG. 7 is a cross-section taken on line 7—7 of FIG. 6.

I claim:

The ornamental design for a shoulder support for telephones, substantially as shown.
